UNITED STATES PATENT OFFICE

PERCELL E. HOSTETTER, OF HANOVER, PENNSYLVANIA

COMBINATION BATHROOM FIXTURE

Application filed May 17, 1929. Serial No. 363,748.

This invention relates to combination bathroom fixtures, and an object of the invention is to provide a substantially unitary structure embodying a bath tub of the so-called built-in type and a casing at one end of the tub for enclosing a toilet fixture or water closet, so that the latter as well as the body of the tub is effectively housed within sanitary, enameled walls which may be readily 10 kept clean, thus preventing the accumulation of dirt and dust on the outside of the toilet bowl and in the waste space surrounding the same, which occurs with the usual exposed toilet and renders the bathroom both un- 15 slightly and unsanitary.

Other objects of the invention are, to provide an improved combination fixture of this character which effects a compact arrangement of the bath tub and toilet fixture and 20 economizes in the space required therefor, to make possible the use of a cheaper type of toilet bowl and thus economize in plumbing expense, and to permit the convenient installation of the toilet fixture within the casing 25 provided therefor and its ready removal therefrom if occasion requires.

The various features of novelty which characterize my invention are pointed out with particularity in the claims annexed to 30 and forming a part of this specification. For a better understanding of the invention, however, and the advantages possessed by it, reference should be had to the accompanying drawing and descriptive matter in which I 35 have illustrated and described one embodiment of my invention.

In the drawing:

Figure 1 is a perspective view illustrating the installation of one embodiment of my 40 invention.

Fig. 2 is a fragmentary plan view thereof, partly broken away.

Fig. 3 is a transverse vertical section on the line 3—3 of Fig. 2.

Fig. 4 is a longitudinal vertical section on the line 4—4 of Fig. 2.

In the present embodiment of the invention, I provide in an integral casting, a body 1 of a bath tub, a rim 2 surrounding the body 50 at the top thereof, and an apron 3 depending

from the rim at the front of the tub and closing the space between the rim and the floor. At one end of the tub, the rim 2 and the apron 3 are extended longitudinally in their respective planes and for a suitable distance 55 to form the top wall 4 and the front wall 5 of a casing 6 for enclosing a toilet fixture or water closet 7. An apron 8 is provided at the exposed end of my improved fixture to form a side wall of the casing 6, closing the space 60 between the adjacent side edge of the top wall 4 and the floor. The top wall 4 is formed with an opening 9 of suitable size to permit the toilet fixture 7 to be inserted therethrough and installed, with suitable pipe connections, 65 within the casing 6. The opening 9 is closed by a cover plate 10 which is supported in any suitable manner, as upon flanges 11 projecting inwardly around the opening and preferably offset below the plane of the top wall 4 70 for a distance equal to the thickness of the cover plate, so that the upper surface of the cover plate will be flush with the upper surface of the top wall 4. By means of screws 12 passing through the cover plate 10 and threaded into the flanges 11, the cover plate 75 is detachably secured in position. An opening 13 of suitable size and shape is formed in the cover plate 10 to expose the seat 14 of the toilet fixture 7, this opening being adapted to 80 be closed by a lid 15 hinged to the cover plate at its rear end, as at 16, and arranged when lowered to fit snugly within the opening, preferably with its upper surface flush with the upper surface of the cover plate. 85

The exposed surfaces of the body 1, rim 2 and apron 3 of the tub, and the top wall 4, front wall 5, side wall 8 and cover plate 10 of the casing 6 and all surfaces of the lid 15, 90 are suitably covered with porcelain enamel to provide a sanitary finish. As shown in the drawing, the apron 3, front wall 5 and side wall 8, may have an ornamental design applied thereto to simulate tile, as is quite 95 usual in finishing built-in bath tubs, but it is to be understood that any such ornamental design forms no part of the present invention and the finish of these parts may be a plain porcelain enamel finish, if desired. 100

From the foregoing description, the use of my invention will be obvious.

Referring to Fig. 3, it will be noticed that I have shown a rear wall 17 to the casing 6, but it is to be understood that this wall is not essential and may be omitted.

Moreover, if the end of my improved combination fixture provided with the casing, abuts against a wall of the room in which the installation is made, the apron or wall 8 may be omitted, and the top wall 4 may be braced or otherwise suitably supported, if necessary, in lieu thereof.

Various other changes may be made in the form, arrangement and combinations of the parts without departing from the spirit and scope of the invention as defined in the appended claims.

Having thus described the invention, what I claim is—

- 20 1. A bathroom fixture comprising a casting providing, in an integral structure, a bath tub of the built-in type and a casing for enclosing a water closet, the casing being formed with an opening through which the water closet may be inserted and removed, and a removable cover plate for closing such opening.
- 25 2. A bathroom fixture comprising a bath tub of the built-in type, having a body, a rim surrounding the same, and an apron at the front of the tub between the rim and the floor, a casing at one end of the bath tub for enclosing a water closet, said casing having top and front walls formed integrally with, and constituted by extensions of, said rim and apron, respectively, and said top wall having an opening therethrough for affording access to the water closet, and a hinged lid for said opening.
- 30 3. A bathroom fixture comprising a bath tub of the built-in type, having a body, a rim surrounding the same, and an apron at the front of the tub between the rim and the floor, a casing at one end of the tub for enclosing a water closet, said casing having top and front walls integral with, and formed by extensions of, said rim and apron, respectively, and said top wall being provided with an opening through which the water closet may be inserted and removed, a cover plate detachably secured to said top wall for closing such opening, said cover plate being formed with an opening for affording access to the water closet, and a lid hinged to said cover plate for closing said last mentioned opening.

In testimony whereof, I have signed my name to this specification.
